UNITED STATES PATENT OFFICE.

AUGUSTUS H. JONES, OF MERIDEN, CONNECTICUT, ASSIGNOR TO THE A. H. JONES COMPANY, OF MERIDEN, CONNECTICUT.

COMBINATION CANDLESTICK.

Application filed May 11, 1926. Serial No. 108,232.

I do hereby declare the following, when taken in connection with the accompanying drawings and the characters of reference marked thereon, to be a full, clear, and exact 5 description of the invention, and which said drawings constitute part of this application, and represent in

Fig. 1 a side view, partly in section, of a combination candlestick constructed in accordance with my invention, and showing it as used with an electric light.

Fig. 2 a similar view with the electric-light plug removed and replaced by a candle-socket.

15 Fig. 3 a side view of the plug and shade-holder removed.

Fig. 4 a side view of a "vigil" light detached.

20 Fig. 5 a side view of the shade-holder detached.

Fig. 6 an enlarged sectional view of the upper end of the candlestick, showing the electrical connections between the plug-socket and lamp.

25 Fig. 7 a top view with the shade-holder and lamp removed.

Fig. 8 a plan view of an adapter.

Fig. 9 a side view of the same.

30 Fig. 10 a broken view showing one side of the upper end of the plug.

Fig. 11 a similar view of the opposite side of the plug.

Fig. 12 a top view of the plug-socket.

35 Fig. 13 a side view of a candlestick detached.

This invention relates to improvement in combination candlesticks, that is, a candlestick which may form a support for an electric light or be used with an ordinary candle, 40 and particularly to combination candlesticks especially designed for use in churches or mortuary parlors, the object being to provide a candlestick in which an electric light may be readily mounted and properly supported and coupled with the source of supply, or removed for the support of a candle, and the invention consists in the construction as hereinafter described and particularly recited in the claim.

50 In carrying out my invention, I employ a standard 15 of any approved design, formed in its upper end with a deep vertical recess 16 in the bottom of which is located a plug-socket 17. This socket is of insulating material and is formed with an annular recess

18 in its upper end, which recess is lined with a ring 19 of metal, and this ring is connected by wire 20 with one of the usual circuit-wires. Arranged in the center of the recess is a stud 21 formed with a stem 22 extending downward through the socket and engaged with the other circuit-wire 23.

Arranged to engage with the plug-socket is a long plug 24 having a reduced lower end 25, which is surrounded by a band 26 of metal, the external diameter of this band corresponding to the internal diameter of the ring 18, into which it closely fits. This band is connected by a wire 27 with the usual lamp-socket 28 mounted in the upper end of the plug, which is of a length to project slightly above the top of the standard. In the center of the bottom of the plug is mounted an inverted cup 29 of metal, adapted to set over and closely fit the stud 21, and this cup 29 is connected by wire 30 extending upward through the plug and into engagement with a contact 31 in the center of the socket 28. The upper end of the plug is externally threaded to mount an ornamental globe-holder 32, which is also supported upon the upper end of the standard. The socket 28 is like a standard socket and adapted to receive an ordinary bulb of any desired candle power.

Oftentimes, a low candle-power lamp is desired when the device is to be used as a so-called "vigil" light, and if so, an adapter 33 may be turned into the socket 28, and in the center of this adapter is an adapter-socket 34 threaded to receive the threaded end 35 of a "vigil" lamp 36, which fits in the globe-holder 32.

In case it is desired to use a regular candle, the plug 24 will be removed and a candle-holder 37 set into the upper end of the standard in position to support a candle, as indicated in broken lines in Fig. 2.

I wish to call particular attention to the fact that the standard has a deep vertical recess in its upper end for the reception of the long plug member which fits into it, so as to be firmly supported in a vertical position and be capable of supporting a comparatively heavy globe-holder and globe, and also that the recess is deep enough to firmly support a candle.

I claim:

A plug-socket formed with a recess in its upper end, lined by a smooth annular ring,

and with a centrally-arranged stud, said ring and stud electrically connected with circuit-wires, a plug having its lower end reduced and surrounded by a smooth band 5 of metal closely fitting the ring in the plug-socket, and provided in its lower end with an inverted metal cup adapted to set over and closely fit the stud on the plug-socket, and a lamp-socket at the upper end of the plug, said band and cup electrically connected with terminals in the lamp-socket. ¹⁰

In testimony whereof, I have signed this specification.

AUGUSTUS H. JONES.
